UNITED STATES PATENT OFFICE.

JOHN H. PHILLIPS, OF CHICAGO, ILLINOIS.

DRILL-CHUCK OR THE LIKE.

1,392,702.

Specification of Letters Patent.

Patented Oct. 4, 1921.

Application filed February 27, 1920. Serial No. 361,903.

To all whom it may concern:

Be it known that I, JOHN H. PHILLIPS, a citizen of the United States, residing at Chicago, in the county of Cook and State 5 of Illinois, have invented certain new and useful Improvements in Drill-Chucks or the like, of which the following is a description.

My invention belongs to that general class of devices known as chucks and relates particularly to a chuck adapted for use with drills used for drilling holes in concrete, stone, brick or the like. The invention has among its objects the production of a device of the kind described, that is 15 simple, convenient, durable, efficient and satisfactory for use wherever found applicable. The same has particularly as an object the production of a chuck of the kind described, applicable for use with tubular drills of the 20 type described in my pending application, Serial No. 312,243, filed July 21, 1919. Many other objects and advantages of the construction herein shown and described will be obvious to those skilled in the art, from the 25 disclosure herein given.

To this end my invention consists of the novel construction, arrangement and combination of parts herein shown and described and more particularly pointed out in the 30 claims.

In the drawings, wherein like reference characters indicate like or corresponding parts,

Figure 1 is a view in elevation and partial sectional view of one form of my chuck with one type of drill positioned therein,

Fig. 2 is a similar view of another form of a chuck,

Fig. 3 is a sectional view taken substantially on line 3—3 of Fig. 2, and

Fig. 4 is a sectional view of a modified form of the same.

As stated, the chucks herein illustrated and described are designed for use with shell drills, shown and described in my pending application, Serial No. 312,243 referred to, and are especially adapted for use with the said drills for drilling "up holes" in concrete ceilings.

When drilling "up holes" with the tubular or core type drills referred to, the cuttings from drill will fall down through bore of drill, thus cleaning by gravity.

The purpose of my invention is to provide 55 chucks or holders that will substantially

hold the different types of shell drills for drilling, and which can be operated by the different kinds of drilling hammers. Said chucks constructed with a bore or passage corresponding to the bore of the drill, said 60 bore terminating in a slot or opening in the side of the chuck at a point below the end of the drill and above the point at which the chuck engages with the hammer or operating mechanism, in such manner that the 65 cuttings will pass down through drill and chuck, and out the side, thus obviating the necessity of removing drill for cleaning.

Referring to the drawings, particularly Fig. 1, 1 represents a chuck head which 70 is formed to suitably engage the drill, as shown, with a flared recess 2, and with an opening or bore 3 extending toward the opposite end of the shank 4, and terminating in the slot or opening in the side of shank, 75 as at 5, to provide an outlet. The end 4 of the shank is constructed in a desired manner to engage a hammer, or equivalent, actuating mechanism for the chuck. As shown at 4' the same is tapered. I have not consid- 80

ered it necessary to illustrate the particular type of hammer or actuating mechanism for operating the chuck, as the same may be of the spring, pneumatic, electric or similar type. The drill shown is tubular and made 85 of one or more parts, and is referred to in my pending application, mentioned as projecting type. This type is designed for drilling holes of a depth corresponding to length of drill from the end substantially 90 to the end of the chuck or intermediate depth. This chuck is particularly suitable to this type of drill in which the tapers of drill and chuck are of such degree as to 95 wedge and hold in rigid contact under action of hammer. The drill illustrated is made in two parts 6, the same being provided with cutting faces, edges, or the equivalent, 7 at the end for engagement with the work to be drilled. If desired the same may be 100 slightly flared as indicated at 8.

The type of chuck illustrated in Fig. 2 is for use with shell drills referred to in my pending application as "flush type". This flush type of drill is designed for drilling holes of a depth equal to the overall length of the drill, so that the chuck end of drill will be flush with surface of the material drilled when the chuck is removed. The purpose of this chuck is to provide a means 105 110

for holding the said flush type drills while the same are operated to drill holes their full depth, and which may be easily removed or disengaged, leaving the shell drill in its own hole.

In Fig. 2, 11 represents a head and 12 a collar or sleeve arranged thereon. In this case the head is tubular, the shank 14 having a bore and side outlet 13 as previously described, through which cuttings will discharge. I have shown a tapered end 15, at the opposite end of the shank, it being understood that this is constructed to fit the particular hammer mechanism in which 15 chuck is to be used. The sleeve or collar 12 is normally supported and maintained in substantially the position shown by a spring 16, or the equivalent, bearing against the shoulder 17 and the end of the sleeve. 20 The drill shown in this figure is in two parts, it being understood that the same may be made in one, two or more parts. The particular drill illustrated is provided with cutting faces 19. The opposite end of the 25 drill is shown with inclined faces at the meeting edges of the parts, and lugs 20 on the head of shank 14 arranged to engage in the spaces between the inclined faces in such manner that the drill may be turned 30 back and forth as required in stone drilling. The sleeve or collar 12 is slidably mounted on the shank or stem 14, and the drill and shank are of the same size, so that sleeve 12 will also be a sliding fit on the drill. 35 The operation of drilling the shell drill into full depths is as follows: The two-piece drill is placed in position as shown in chuck, the sleeve holding same assembled and in line; the drill is then held in contact with 40 work to be drilled and operated by the desired type of hammer. When the hole is drilled in a little way the sleeve 12 comes in contact with surface being drilled and comes to rest, the drill and shank 14 sliding through it as the hole progresses, the 45 spring yielding accordingly, the sleeve acting to hold the two part drill assembled until the same is well advanced in the hole after which the walls of the hole act as 50 guide. The sleeve continues to hold the drill in line and engagement with the head 11, in such manner that lugs 20 will operate to turn drill until same is flush with surface.

55 In Fig. 4, I have illustrated a simple form of a similar chuck in which 21 represents the head and shank of tubular construction and provided with an outlet 22 for the discharge of the cuttings. In this 60 type, however, the collar or sleeve is rigidly mounted on the head of shank in the position shown. 25 are lugs similar to lugs 20. In this case I have shown a single piece drill 26, also of the projecting type, but 65 with a straight instead of tapered end pro-

jecting into chuck, and with notches for engagement with lugs 25. While the drill shown is of one piece it is understood it may be made in one or more parts and provided with cutting faces or edges 27. It is 70 unnecessary to describe the drill in detail other than to say that it is designed to be drilled in until the end of the chuck comes in contact with the work surface, when the chuck is removed and the drill left in the 75 holes it drilled, where it is utilized as an expansion shell for carrying hangers, etc., as set forth in my co-pending application referred to.

With different types of tubular drills and 80 hammers, or actuating mechanism it may be necessary or desirable to modify the chuck in unessential details, and I also wish to state that the small sizes of tubular drills with finer pitch cutting edges, do not necessarily require the back and forth turning while drilling, as in this type of drill, the jump or vibration from blow of hammer is sufficient to alter position or contact, so that lugs 20 and 25, as previously described, may not be required. I have not considered it necessary herein to point out the various styles and types of drills and actuating mechanisms which may be used 90 with the chuck.

Having thus described my invention, it is obvious that various immaterial modifications may be made in the same without departing from the spirit of my invention; hence I do not wish to be understood as 100 limiting myself to the exact form, construction, arrangement and combination of parts herein shown and described or uses mentioned.

What I claim as new and desire to secure 105 by Letters Patent is:

1. In a drill chuck of the kind described and in combination, a shank having a head constructed to engage a drill, and a drill supporting member adapted to surround said drill and slidably on said shank away from said drill.
2. In a device of the kind described and in combination, a shank constructed at one end to engage a drill, and a sleeve adapted to embrace said drill to support it and slidably on said shank away from said drill.
3. In a device of the kind described and in combination, a drill chuck consisting of a shank having a head constructed to engage the drill end and provided with an opening extending from the head and to a point below the head and having an outlet to the exterior of the shank, and means for yieldably supporting said drill beyond said shank head.
4. In a drill chuck of the kind described and in combination, a shank constructed at one end to engage with the drill end and having a sleeve slidably arranged thereon,

means for maintaining said sleeve in operative position, said shank having an opening therein extending from the said end toward the opposite end and terminating at the exterior of the shank.

5. In a drill chuck of the kind described and in combination, a shank constructed at one end to engage with the drill end and having a sleeve slidably arranged thereon, 10 yieldable means for maintaining said sleeve in operative position, said shank having an opening therein extending from the said end toward the opposite end and terminating at the exterior of the shank.
15. 6. In a drill chuck of the kind described and in combination, a shank constructed at one end to engage with the drill end and having a sleeve slidably arranged thereon, a spring arranged on said shank and yield- 20 ably engaging said sleeve for maintaining said sleeve in operative position, said shank having an opening therein extending from

the said end toward the opposite end and terminating at the exterior of the shank.

7. In a device of the kind described and in combination, a shank, a recessed head arranged at the end of said shank and adapted to slidably receive and frictionally maintain a drill therein, said recessed portion and tool having no interengaging drill-retaining 30 projections therebetween, the opposite end of said shank arranged to engage a coöperating mechanism, said shank provided with an opening extending from the head to the exterior of the shank at a point below 35 said head for the discharge of material from the drill carried by the head.

In testimony whereof, I have hereunto signed my name in the presence of two subscribing witnesses.

JOHN H. PHILLIPS.
